UNITED STATES PATENT OFFICE

149,391

DESIGN FOR A LAMP SHADE

Geneva U. Van Brunt, North Wilbraham, Mass.

Application February 5, 1947, Serial No. 136,692

Term of patent 7 years

(Cl. D48—16)

To all whom it may concern:

Be it known that I, Geneva U. Van Brunt, a citizen of the United States, residing at North Wilbraham, in the county of Hampden and Commonwealth of Massachusetts, have invented a new, original, and ornamental Design for Lamp Shades, of which the following is a specification, reference being had to the accompanying drawing, forming a part thereof.

Referring to the drawing:

Figs. 1 and 2 are front and rear elevational views respectively, of a lamp shade showing my new design.

I claim:

The ornamental design for a lamp shade, as shown.

GENEVA U. VAN BRUNT.
